UNITED STATES PATENT OFFICE.

THOMAS FITZGERALD, OF FREDONIA, NEW YORK.

JOINT-FILLING MACHINE.

1,052,578.

Specification of Letters Patent. Patented Feb. 11, 1913.

Application filed October 10, 1910. Serial No. 586,147.

To all whom it may concern:

Be it known that I, THOMAS FITZGERALD, a citizen of the United States, residing at Fredonia, in the county of Chautauqua and 5 State of New York, have invented a new and useful Improvement in Joint-Filling Machines, of which the following is a specification.

This invention relates to improvements 10 in portable machines or devices of the sort disclosed in my Patent No. 805,719, dated November 7, 1905, which are used in the construction of pavements for pouring melted tar, pitch or other analogous binding or 15 filling material into the joints or crevices between the paving bricks or blocks.

The objects of the invention are to produce a practical, desirable and efficient machine or device for this purpose which can 20 be readily and rapidly operated to pour the material into the crevices without spreading it over the surface of the pavement, so as to waste the material and make the pavement objectionable; also to construct the machine 25 or device so that the material will be kept in a liquid condition suitable for pouring and so that jointed discharge spouts are not required in order to properly direct the material into the crevices; and also to make 30 provision for adjusting the discharge spouts to adapt the machine or device for use on pavements in which the crevices are differently spaced.

For the sake of brevity and clearness, the 35 filling material will be hereinafter referred to as "tar" but it will be understood that any suitable filling or binding material can be used.

The machine or device comprises an inner 40 holding vessel for the tar provided with one or more discharge spouts and arranged in an outer vessel or casing furnished with a burner for heating the tar vessel and discharge spout to keep the tar in a liquid condition and insuring a free discharge thereof. The outer vessel or casing is mounted on a 45 wheeled truck or carriage adapted to be pushed over the pavement, and the inner vessel is hung or movably supported in the outer casing so that the discharge spout is capable of being shifted laterally so as to be always held directly over the crevice by a guiding wheel or device arranged to travel in the crevice and control the position of 55 the spout. Means are provided for control-

ling the discharge of the material as required and for raising and lowering the guide device out of and into operative position. When the machine is furnished with a plurality of discharge spouts for simultaneously filling two or more crevices, the spouts and their guide devices are made adjustable to suit differently spaced crevices and valves are provided for independently controlling the discharge of the tar from the 60 several spouts.

In the accompanying drawings, consisting of three sheets: Figure 1 is a side elevation, partly in section, of a multiple spout pouring machine embodying the invention. Fig. 70 2 is a longitudinal sectional elevation thereof. Fig. 3 is a plan view thereof. Fig. 4 is a fragmentary transverse sectional elevation on an enlarged scale. Fig. 5 is an enlarged plan view, partly in section, of the 75 spout guiding devices. Fig. 6 is a section of the adjusting means for the guide wheels. Fig. 7 is an enlarged section of one of the pivotal supports for the inner vessel. Fig. 8 is an enlarged fragmentary section of 80 one of the discharge spouts and valves. Fig. 9 is an enlarged fragmentary side elevation, partly in section, of a single spout machine. Fig. 10 is a transverse sectional elevation thereof. 85

Like reference characters refer to like parts in the several figures.

A represents an outer vessel, tank or casing of any suitable construction which is supported by or constitutes a part of a truck 90 or carriage having wheels B whereby the machine or device can be moved along over the pavement. In the construction shown, the casing A, which consists of an upright metal cylinder having an open upper end, 95 is provided at opposite sides with stud axles or trunnions b on which the wheels B are journaled.

C represents push handles which are secured to and project rearwardly from brackets c to which the axles are secured. The handles are preferably offset or bent toward one side of the machine so that the operator in pushing the machine can walk at one side of the crevices being filled by the 105 machine and thus avoid stepping on the soft tar.

D represents the inner tank or vessel which contains the tar and which is provided with one or more discharge spouts 110

depending from the lower end thereof through the bottom of the outer casing, and which is movably supported in the outer casing A so that it is free to shift laterally. 5 For instance, the inner vessel is pivotally supported by screws d secured to the upper portion of the outer casing at the front and rear thereof and passing through holes in the depending rim of a flange d' which 10 projects outwardly from the upper end of the inner vessel over the upper edge of the outer casing. In the machine illustrated in Figs. 1-8, two discharge spouts E are provided for simultaneously filling two crevices, 15 while in the machine shown in Figs. 9 and 10 only one spout is provided. The bottom of the inner vessel preferably inclines downwardly toward the discharge spout or spouts to facilitate the discharge of the tar. By 20 thus hanging or mounting the inner vessel in the outer casing, the lower end thereof is adapted to be shifted sidewise so that the discharge spout or spouts can be guided by suitable means to follow or be held always 25 directly over the crevice or crevices to direct the tar thereinto as the machine is moved along.

The discharge spouts E are secured to the inner vessel in any suitable way which enables them to be adjusted toward or from 30 each other to suit differently spaced crevices. For instance, the spouts are secured to slides e which are adjustable in a guideway e' on the bottom of the inner vessel D by means 35 of adjusting screws e^2 which project out through the outer casing A.

The means shown for guiding the discharge spouts comprise front guide wheels F and a rear guide wheel F', there being 40 one front guide wheel for each spout arranged in front of the spout to travel in the crevice into which the spout pours the tar. The rear guide wheel F' is preferably located in rear of the outer casing A where 45 it can be readily seen by the operator and kept in one of the crevices of the pavement to facilitate the guiding of the machine. This wheel is arranged to travel in one of the crevices at one side of the crevices into 50 which the spouts discharge and therefore does not roll in the freshly discharged tar. In the construction shown, see particularly Figs. 4-6, the guide wheels are adjustably mounted on a frame f which is secured at 55 its front end to a spring plate f' attached to the bottom of the outer casing A and to which the discharge spouts E are adjustably fastened. The front guide wheels are journaled on an axle f^2 seated at its 60 ends in hollow adjusting screws f^3 which are screwed into threaded holes in the side bars of the frame f . The guide wheels F are held against the inner ends of the adjusting screws f^3 by a spring f^4 surrounding 65 the axle between the wheels, so that the

wheels will be moved apart by unscrewing the adjusting screws f^3 , and moved nearer together by screwing in the adjusting screws. The adjusting screws are held, when adjusted, by jam-nuts f^5 . The guide wheels can thus be adjusted correspondingly to the discharge spouts when the latter are adjusted to fill crevices which are differently spaced. The discharge spouts are secured to the side bars of the frame f by adjustable 70 eye-bolts f^6 which permit the described adjustments of the spouts but hold them rigid with the frame f when adjusted. The rear guide wheel F' is journaled on one end of an axle f^7 which is adjustably secured at its opposite end to one of the side bars of the frame f by nuts f^8 and passes through a bearing hole in the other side bar of the frame. As the discharge spouts are connected by the frame f to the guide wheels 75 they will be caused to follow in the paths traversed by the front guide wheels F, and as these guide wheels travel in the crevices to be filled they act to hold the spouts directly over the crevices. There is sufficient 80 looseness or play between the parts of the machine to allow the movement of the spouts necessary for them to accommodate themselves to the ordinary irregularities of the 85 crevices. 90

By movably mounting or hanging the inner vessel in the outer casing as described, rigid discharge spouts can be employed which are desirable as they have no joints which are liable to become clogged by the 95 tar.

G, Fig. 2, represents a lever or handle for moving the frame f to lift the guide wheels out of or lower them into operative position. This lever, in the machine shown, is pivoted 105 on one of the handle bars C and is connected by a rod g to a bell-crank lever g' which is fulcrumed on the handle bar and is connected by a rod or link g^2 to the rear end of one of the side bars of the frame f . 110

g^3 is a hook or device adapted to be engaged by the lever G for holding the guide wheels in their elevated position. Any other suitable means can be employed for raising and lowering the guide wheels. 115

H represents a valve with which each discharge spout is provided for regulating the discharge of the tar. The valve shown is connected to the lower end of a rod h which is pivoted at its upper end to a bell-crank lever h' fulcrumed on the upper portion of the inner vessel D and is connected by a rod h^2 to an operating lever or handle h^3 . The valve operating lever h^3 for one valve is preferably fulcrumed on one of the push handles C of the machine, while the operating lever h^3 for the other valve is similarly fulcrumed on the other push handle of the machine, so that the levers can be readily operated by the fingers without removing 120 125 130

the hands from the push handles to independently regulate the discharge from the spouts.

I, Fig. 2, represents a burner, which may be of any suitable construction, for heating the inner vessel and the discharge spouts to keep the tar in a liquid condition and insuring a free discharge of the same through the discharge spouts. A liquid or gaseous fuel burner is illustrated which is arranged in the outer casing below the inner vessel so as to direct the flame against the bottom of the inner vessel and the discharge spouts. The hot gases ascend through the space *i* between the vertical walls of the inner vessel and casing, the latter thus serving as a heating jacket for the inner vessel and facilitating the heating of the inner vessel and its contents. The burner is supplied with fuel by a pipe *i'* from a suitable reservoir *i''* located in any convenient position on the machine. Any other suitable means for heating the inner vessel can be used. The filling material is ordinarily poured into the inner vessel *D* in a melted or liquid condition and it is only necessary to supply heat enough by the burner *I* to keep the material hot and in a liquid state.

K represents a strainer or screen of any suitable kind through which the material is poured into the inner vessel for removing therefrom any solid particles or foreign matter.

The invention, in so far as the described manner of movably mounting the containing vessel and guiding the discharge spouts is concerned, is not restricted to the use of the outer casing or heat jacket, and on the other hand, discharge spouts of different construction and other means for guiding the spouts can be used in connection with an inner vessel arranged in an outer casing provided with means for heating the inner vessel.

45 I claim as my invention:

1. In a machine for the purpose stated, the combination of a portable casing, an inner vessel movably supported in said casing to move laterally, a discharge spout for said inner vessel, and a guide device for said spout arranged to travel on a guiding surface as the machine is moved along and shift said inner vessel and spout to cause said spout to follow the direction traversed by said guide device, substantially as set forth.

2. In a machine for the purpose stated, the combination of a portable casing, an inner vessel movably supported in said casing to move laterally, a discharge spout for said inner vessel, and a guide device for said spout depending below said casing and arranged to travel in a crevice in a pavement as the machine is moved along the pavement and shift said inner vessel and spout to cause

the spout to follow and discharge into the crevice, substantially as set forth.

3. The combination of a casing, supporting wheels therefor, an inner vessel hung in said casing to swing laterally, a discharge spout for said inner vessel, and a guide device arranged to travel on a guiding surface for guiding said spout as the machine is moved along, substantially as set forth.

4. The combination of a casing, supporting wheels therefor, an inner vessel hung in said casing to swing laterally, a discharge spout depending from said inner vessel through said casing, and a guide device mounted on said casing and arranged to travel on a guiding surface and connected to said spout for guiding the same as the machine is moved along, substantially as set forth.

5. The combination of a wheeled carriage, a vessel hung on said carriage so as to be free to swing laterally with regard to said wheels, a discharge spout for said vessel, and a guide device arranged to travel on a guiding surface and shift said vessel for guiding said spout as the machine is moved along, substantially as set forth.

6. The combination of a wheeled carriage, a vessel hung on said carriage to swing laterally, a plurality of discharge spouts for said vessel, means for adjusting said spouts to different distances apart, and a guide device arranged to travel on a guiding surface for guiding said spouts as the machine is moved along, said guide device being adjustable to correspond with the adjustment of said spouts, substantially as set forth.

7. The combination of a wheeled carriage, a vessel hung on said carriage to swing laterally, a plurality of discharge spouts for said vessel, means for adjusting said spouts to different distances apart, guide wheels for said spouts arranged to travel in crevices in the pavement and connected to said spouts for guiding the latter as the machine is moved along, and means for adjusting said guide wheels to correspond with the adjustment of said spouts, substantially as set forth.

8. In a machine for the purpose stated, the combination of a portable casing, an inner vessel pivotally mounted in said casing, a discharge spout for said inner vessel, means in said casing for heating said inner vessel, and a guide device arranged to travel on a guiding surface for guiding said spout as the machine is moved along, substantially as set forth.

9. In a machine for the purpose stated, the combination of a portable casing, an inner vessel movably supported in said casing to move laterally, a discharge spout for said inner vessel, means in said casing for heating said inner vessel, and a guide device arranged to travel on a guiding sur-

face for guiding said spout as the machine is moved along, substantially as set forth.

10. In a machine for the purpose stated, the combination of a portable casing, an inner vessel movably supported in said casing to move laterally and spaced from the bottom and side walls of said casing, a burner in said casing below said inner vessel for heating said vessel, a discharge spout for said inner vessel, and a guide device arranged to travel on a guiding surface for guiding said spout as the machine is moved along, substantially as set forth.

11. In a machine for the purpose stated,

the combination of a vessel, a wheeled carriage therefor, a discharge spout for said vessel, a guide device for said spout arranged to travel on a guiding surface for guiding said spout as the machine is moved along, and means for raising said guide device out of and lowering it into operative position, substantially as set forth. 15 20

Witness my hand, this 3rd day of October, 1910.

THOMAS FITZGERALD.
